COMBINED RESONATOR AND NOZZLE FOR ACOUSTIC TREATMENT OF LIQUIDS

Norman C. Pickering, Sag Harbor, N.Y., and Emil Watro,
792 Nightingale Ave., West Hempstead, N.Y.

Filed Aug. 26, 1963, Ser. No. 76,355

Term of patent 14 years

(Cl. D91—1)

FIG. 2

FIG. 1

FIG. 3

FIG. 4

FIG. 5

FIG. 1 is a front elevational view of a combined resonator and nozzle for acoustic treatment of liquids showing our new design;

FIG. 2 is a side elevational view thereof;

FIG. 3 is another side elevational view opposite to the side of FIG. 2;

FIG. 4 is a plan view as seen from the top of FIG. 1; and

FIG. 5 is a plan view as seen from the bottom of FIG. 1.

The side opposite FIG. 1 (not shown) is the same as FIG. 1.

We claim:

The ornamental design for a combined resonator and nozzle for acoustic treatment of liquids, substantially as shown and described.
